UNITED STATES PATENT OFFICE.

FRANK L. GILMAN AND WILLIS M. BAUM, OF LOS ANGELES, CALIFORNIA.

CURRENT-MOTOR.

1,353,906.

Specification of Letters Patent. Patented Sept. 28, 1920.

Application filed February 25, 1918, Serial No. 219,042. Renewed February 12, 1920. Serial No. 358,132.

To all whom it may concern:

Be it known that we, FRANK L. GILMAN and WILLIS M. BAUM, both citizens of the United States, and residents of Los Angeles, 5 county of Los Angeles, State of California, have invented certain new and useful Improvements in Current-Motors, of which the following is a specification.

Our invention relates to mechanism for 10 utilizing the flow of streams to develop power and was designed primarily for the purpose of utilizing the power thus developed to operate a pump or pumps, the pumps in turn being used to pump water out 15 of the stream to be used for various purposes such as irrigating, sluicing in mining and the like and the object thereof is to produce mechanism for this purpose which will be simple in construction and operation and 20 which will continue in operation with a minimum of attention.

A further object is to provide a device of 25 this character which can be constructed in units, these units to be connected together to provide greater or less power as desired.

Other objects and advantages will appear hereinafter and while we have shown and 30 will describe the preferred form of our invention, it will be understood that we do not limit ourselves to such form but that various changes and adaptations may be 35 made therein without departing from the spirit of our invention.

We accomplish the above objects by the 40 mechanism described herein and illustrated in the accompanying drawings forming a part hereof in which—

Figure 1 is a top plan of a form of our invention.

Fig. 2 is a side elevation of Fig. 1.

Referring to the drawings our device comprises two elongated cylindrical floats or pontoons 30 and 31, which normally lie lengthwise of the stream, being anchored in 45 position by cables 47, 48, 49, and 50. Near each end on the underside of said pontoons 30 and 31 are secured downwardly extending, oppositely disposed, L-shaped hangers 33 and 34. Secured near their ends to the 50 free ends of hangers 33^a and 34, transversely of the pontoons 30 and 31 are guide rails or tracks 32 and 33, (best shown in Fig. 2) and upon these rails are mounted carriages 35 and 36, by means of grooved 55 wheels 37 and 38, to travel longitudinally. Secured, at a distance from each end, to the

lower end of carriages 35 and 36, to extend parallel with rails 32 and 33, are cross rails 40 and 42, and pivotally secured intermediate their ends to the underside of said cross rails are a plurality of propeller blades 13. It will be noted that blades 13 are pivoted to cross rails 40 and 42 so that the upstream ends are longer than the downstream ends, the purpose of which is to offer a greater 65 area of said blade to the action of the current on the upstream side of its pivot so that as soon as the blade reaches a point a little past the longitudinal center when being reversed the greater area of resistance 70 will cause the water to quickly force the blades to their maximum position. Blades 13 are mounted to normally lie slightly angular to the longitudinal direction of the current and pontoons and have their free 75 ends connected together in equally spaced relation by tie bars 43.

Pivotal secured at one of its ends to the upper face of cross rail 40, near one end thereof is a reversing bar 41, the other end 80 of which extends to a point a little beyond cross rail 42. Intermediate its ends reversing bar 41 is provided with a longitudinally extending slot 44 in which is mounted the free end of a pin 45 secured to and extending 85 upwardly from the tie bar 43 which connects the upstream or longer ends of the blades 13 of the cross rail to which it is pivoted. A pin 46 extends upwardly from cross rail 42 at one side of the free end of reversing bar 90 41, and a similar pin 46^a extends upwardly from said rail at the other side of said bar. A similar reversing bar 41^a and adjunct parts are provided for cross rail 42. The free ends of rails 40 and 42 are connected 95 in any suitable manner to the piston of a pump or any other device for taking off the power developed by the motor.

In the operation of our motor.

As shown in the drawings, the lower end 100 of Fig. 1 being the upstream end, cross rail 40 has reached the limit of its travel to the left, and has just reversed the direction of the blades mounted on cross rail 42, it being understood that owing to the upstream ends of 105 the blades being longer than the downstream ends it is only necessary to move the blades a little past the longitudinal center thereof when the action of the current will complete the movement. Rail 42 will then 110 start to move across the stream to the right and pin 46 will engage the free end of bar

41 of rail 40 and reverse the direction of its blades, it being understood that this reversing takes place just before rail 42 reaches its limit of movement. Rail 40 will then start 5 to move across the stream to the right and pin 46^a on said rail will, at the proper time, engage the free end of reversing bar 41^a, and upon further movement of rail 40, reverse the blades 13 of rail 42, when rail 42 will 10 commence to move across the stream to the left. Continued movement of rail 42 will cause pin 46^a thereon to engage the free end of reversing bar 41 and reverse the direction of the blades 13 of rail 40, when said 15 rail will commence to move across the stream to the left, pin 46 on rail 40 engaging the free end of reversing bar 41^a and reversing the blades of rail 42. This motion will be continuous as long as the water in 20 the stream flows, first one and then the other rail and its blades being forced across the stream and being reversed as above described.

Having described our invention what we claim is:

A current motor comprising a pair of pontoons anchored in parallel relation on opposite sides of a stream; a pair of guide rails connecting said pontoons at each end thereof; a traveling carriage mounted at 30 each end of each of said pair of rails and extending downwardly therefrom; a cross rail carried by each pair of said carriages; a plurality of propeller blades pivotally mounted intermediate their ends on the underside of said cross rails; cross bars connecting the free ends of said propeller blades; means actuated by said propeller blades for reversing the same; and a connection from said propeller blades to transmit 35 the power developed thereby.

In witness that we claim the foregoing we have hereunto subscribed our names this 15th day of February 1918.

FRANK L. GILMAN.
WILLIS M. BAUM.
